UNITED STATES PATENT OFFICE

DANIEL H. MURPHY, OF WEST HARTFORD, CONNECTICUT, ASSIGNOR TO THE WIRE-MOLD COMPANY, OF HARTFORD, CONNECTICUT, A CORPORATION OF CONNECTICUT

TUBULAR FABRIC

Application filed November 16, 1928. Serial No. 319,885.

This invention relates to tubular fabrics formed in part or entirely of soft, readily compressible strands of crumpled paper.

It has been proposed heretofore to form 5 tubular fabrics of relatively large twisted strands of paper interlocked with smaller binder strands to form a jacket or tube, and the present invention relates to a tubular paper fabric in which further advances are 10 secured by forming at least one set of the interlocked strands of soft, readily, compressible strips of crumpled paper.

The crumpled paper employed in carrying out the present invention is readily formed 15 from narrow, ribbon-like strips of paper that are crumpled to form more or less rounded strands that are soft and flexible and may be readily compressed to cause them to spread laterally under pressure.

20 These soft readily compressible paper strands may be braided or woven with other strands to form a tough and durable tube or jacket that is well adapted for use as a protecting covering for insulated conductors and 25 for various other purposes, and the tendency of these soft strands to spread laterally under pressure serves to increase the covering effect of the fabric. That is, if the paper strands of the tubular fabric are disposed in 30 spaced relation to each other their tendency to spread laterally under pressure will decrease the spaces between the adjacent strands and thus improve the covering effect of the fabric, while if these strands of crumpled paper are secured close together in the 35 fabric they will spread laterally to close the interstices between the crossing strands and thereby form a substantially impervious jacket.

40 These soft crumpled strands of paper form an excellent protecting surface and can be produced at low cost. Furthermore, large strands of the crumpled paper that will build up rapidly in the fabric may be used to advantage in forming tubing since these large 45 strands will spread laterally under pressure to close the spaces between the adjacent strands, and will present a relatively smooth surface at both the inner and outer faces of 50 the fabric.

The various features of the invention will be best understood from the following description when read in connection with the accompanying drawings illustrating good practical forms of the invention.

55 In the drawings:—

Fig. 1 is a side view of a flat strip of paper the lower portion of which is crumpled to form a rounded soft readily compressible strand;

60 Fig. 2 is a perspective view of a braided tube having one set of strands formed of the crumpled paper of Fig. 1;

65 Fig. 3 is a transverse sectional view through the tube of Fig. 2;

70 Fig. 4 is a perspective view of a modified construction showing a tubular braid in which both sets of strands are formed of crumpled paper; and

75 Fig. 5 is a transverse sectional view of Fig. 4;

80 A tubular fabric constructed in accordance with the present invention may be braided or otherwise constructed of interlocked strands of soft crumpled paper, and the fabric may 75 be formed in part or entirely of these paper strands as desired.

85 The soft readily compressible strand 10 of crumpled paper may be formed from a flat strip or narrow sheet of paper 11, and the strip of paper 11 may be easily crumpled into the desired soft untwisted strand by passing it through a die as shown in my co-pending application, Ser. No. 319,884 filed Nov. 16, 1928, since matured into Patent No. 1,760,768, dated May 27, 1930.

90 In the embodiment of the invention shown in Fig. 2, relatively large strands of crumpled paper 10 extend spirally about the tube in one direction and are interbraided with small strong strands of cotton or the like 12. In this construction the paper strands 10 are laid side by side in contacting relation so that the tendency of the soft strands to spread laterally under pressure serves to completely close the cracks or apertures between the strands 10 and at the points at which the binding strands 12 pass between the paper strands 10.

95 It is not essential, however, in all embodi- 100

ments of the invention that the paper strands be disposed in contacting relation with each other, since in some constructions it may be desirable to lay these strands in spaced relation to form an open fabric that will build up rapidly. In such open construction the soft paper strands will spread laterally to improve the covering effect of the fabric and to increase the smoothness of the inner and outer surfaces of the tubular fabric, and this is true whether the fabric is braided or otherwise constructed.

In the modified construction of Figs. 4 and 5 an all-paper braid is shown as constructed of soft crumpled paper strands 10 that are interbraided with smaller strands of crumpled paper 13. It will be apparent, however, that both sets of strands 10 and 13 may be of the same size if desired, and the strands may be braided tightly together as shown to form a closed braid, or if desired the strands may be arranged to form an open braid. It will also be apparent that the strands 10 and 12 of Fig. 2 may be interbraided in any preferred or well known manner, and the same is true of the strands 10 and 13 of Fig. 4.

Tubular fabric constructed in accordance with the present invention may be employed as a protecting covering for electric conductors and for various other purposes and is shown in Fig. 4 as forming a protecting jacket for an electric conductor 14 which is enclosed in the insulating material 15.

A tubular fabric constructed of untwisted strands of crumpled paper in accordance with the present invention is tough and durable, may be produced at low cost, will build up rapidly in the formation of the tube, and as a result of the spreading tendency of the paper strands will produce a substantially impervious fabric or jacket having a comparatively smooth inner and outer surface.

What is claimed is:—

1. A flexible conduit comprising a tubular fabric formed of binding strands and substantially untwisted strips of paper that are crumpled into rounded strands which are sufficiently soft and compressible to spread laterally to a pronounced degree between and partly around the binding strands to close the interstices in the tubular fabric, and the soft crumpled strands of paper being interlocked with the binding strands so that the latter sink deep in the paper strands to facilitate the closing of the interstices in the fabric.

2. A flexible conduit comprising a tubular fabric formed of binding strands and substantially untwisted strips of paper that are crumpled into soft, readily compressible strands adapted to spread laterally to a pronounced degree in the fabric under pressure, so as to bulge between the binding strands and close the interstices in the fabric, and

interlocked with the binding strands that sink deep into the paper strands to form a tubular fabric in which the strands of one set are well embedded in the strands of the other set.

3. A flexible conduit comprising a tubular fabric formed of substantially untwisted strips of paper that are crumpled into soft readily compressible strands adapted to spread laterally to a pronounced degree in the fabric under pressure, to close the interstices in the fabric, and interlocked with other strands of soft crumpled paper to form an all-paper tubular fabric in which the strands of one set are well embedded in the strands of the other set.

4. A flexible conduit comprising a tubular fabric formed of relatively large untwisted strands of soft crumpled paper interlocked with smaller binder strands and the paper strands being adapted to spread laterally to a pronounced degree in the completed fabric and to spread between and partly around the crossing strands so as to form a coarse tubular fabric that will produce rapidly and at the same time has the interstices between the strands tightly closed.

5. A braided tubular fabric formed of binding strands and substantially untwisted strips of paper that are crumpled into soft, thick, readily compressible strands adapted to spread laterally to a pronounced degree in the fabric under pressure, so as to bulge between the binding strands and close the interstices in the fabric, and interbraided with the binding strands that sink deep into the paper strands to form a coarse braid that will produce rapidly and at the same time has the apertures between the strands tightly closed.

In testimony whereof, I have signed my name to this specification.

DANIEL H. MURPHY.
